SPINNING BASEBALL DEVICE

Chester J. Samuel, Detroit, Mich.

Application September 4, 1959, Serial No. 57,441

Term of patent 14 years

(Cl. D34—15)

Fig. 1 is a top plan view of a spinning baseball device embodying my new design; and

Fig. 2 is a side elevational view; and

Fig. 3 is a side elevational view when the ball and pennant portion thereof are in a spinning attitude; and

Fig. 4 is a sectional view taken on the line 4—4 of Fig. 3 showing only the ball and pennant portion in a spinning attitude.

The dominant features of my design resides in the portions shown in full lines.

I claim:

The ornamental design for a spinning baseball device, substantially as shown and described.
